UNITED STATES PATENT OFFICE.

HENRY D. SCHALL, OF DETROIT, MICHIGAN, ASSIGNOR TO DETROIT STOVE WORKS, OF DETROIT, MICHIGAN, A CORPORATION OF MICHIGAN.

RANGE.

1,339,478.

Specification of Letters Patent. Patented May 11, 1920.

Application filed November 30, 1917. Serial No. 204,533.

To all whom it may concern:

Be it known that I, HENRY D. SCHALL, a citizen of the United States of America, residing at Detroit, in the county of Wayne 5 and State of Michigan, have invented certain new and useful Improvements in Ranges, of which the following is a specification, reference being had therein to the accompanying drawings.

- 10 This invention relates to ranges and refers more particularly to ranges of the hotel or other large sizes, although the invention in its broader aspects is not limited to the type of heating apparatus mentioned.
- 15 Among the objects of the invention are to provide a new and improved construction whereby the stove top comprises sections having different degrees of heat so that one section can be used for cooking at high temperature, another at a lower temperature and preferably another at a still lower temperature for warming purposes; to provide a construction wherein the burners are constructed and arranged to operate substantially as Bunsen burners and with the flame cone terminating just below the top section, which has the greatest degree of heat; to provide ribs or other suitable supporting members on the burner block for supporting 25 the top plate so that the supports for the latter cannot be burned out.
- 30 The invention also resides in the novel construction of the oven section and its arrangement with relation to the top section; in the construction of the joints between the various insulator sections of the oven so that dissipation of heat is prevented; in the provision of a baffle on the top wall of the oven which also serves as a support for the top 35 plate; in the arrangement of this baffle and the graduated passage between the top wall of the oven and the top plate so as to produce an even distribution of the heat and conserve the heat units; in the novel construction of the oven floor or pan; and in such other features of construction and arrangements and combinations of parts as will more fully hereinafter appear.

In the drawings:

- 50 Figure 1 is a vertical sectional view through a range embodying my invention; Fig. 2 is a top plan view of the construction shown in Fig. 1; Fig. 3 is a vertical sectional view on the line 3—3 of Fig. 1;

Fig. 4 is a vertical sectional view on the line 4—4 of Fig. 1;

Fig. 5 is an enlarged perspective view of one of the burner blocks;

Fig. 6 is a perspective view of the oven plate.

Describing in detail the construction shown in the drawings, A designates a range having an open-top plate B and an oven C, the latter being positioned beneath one part 65 of the top plate. For supplying heat to the top plate I preferably employ a plurality of burners D which extend upwardly from supply pipes D', the supply of gas to which is controlled by suitable shut-off valves D². 70 These valves are preferably located in a line at the front of the stove and control the supply from the main pipe or feed line D³.

As shown in Fig. 1 the top plate B is formed in three sections B', B² and B³ 75 which are supported at their edges in grooves or seats E formed in the top flange E' of the body A', which latter may be formed of sheet-metal or other suitable construction.

For retaining the heat in close proximity to the top plate and preventing its dissipation below the plane of the burners, I employ a burner-block F of suitable refractory material, which block is provided with vertical openings F' through which the burners D extend. It will be noticed that the openings are of a sufficiently greater diameter than the burner to permit of a surrounding air passage through which the air from the 85 chamber G is supplied to the burner in a manner similar to the well-known Bunsen burner. This construction has the further advantage, in that the air in passing upward around the burner tends to extract 90 heat therefrom and thus cool the burner pipes as well as preheat the air.

It will be noted that the section B' of the top plate is located directly above the burners D, the space in between being just sufficient to have the top plate clear the top of the blue flame cone of the burners. This will produce an intense heat on the burner section B' while the hot gases of combustion will then pass from the chamber below the section B' to the chamber below the section B² and from there to the chamber below the section B³. The chambers below the sections B² and B³ taper toward the back so that the gas passage is more restricted as 105 110

it nears the flue or outlet G'. This tapering passage is produced by varying the thickness of the insulating blocks H and H' forming the top of the oven, and to facilitate the even distribution of heat these blocks are also provided with diagonally-extending deflecting flanges or ribs I. The latter extend upwardly from the sections H and H' and serve both to compel the gases to travel throughout substantially the entire area of the sections B² and B³ and also serve as a support for these open-top sections.

As shown in Fig. 2 the ribs I and I' are preferably spaced at one end from the side walls of the range so as to permit part of the gas to go on one side while deflecting a predetermined portion toward the other side of the range. The insulating block F is also provided with supporting ribs or projections F² which serve to support the section B' of the top plate. Thus the entire top plate is supported not only by the ledge E but also by the ribs or flanges formed on the refractory blocks, which being indestructible by heat form a permanent support for the top plate.

While the heat to the various sections of the top plate can be varied to suit the temperatures desired, it has been found possible with a range of this kind to maintain the front section B' at about 1300° F., the center section B² at 850° F. and the rear section B³ at about 500° F. When these high temperatures are reached the stack temperature is only about 200°: these temperatures, of course, being simply illustrative. Also the novel arrangement of the passageways and the baffles beneath the sections B² and B³ allows all the heat units to be advantageously employed.

Referring now in detail to the oven construction, it will be noticed that the side walls and bottom sections J, J' and J² are formed of heat-insulating blocks which are preferably made in sections having interlocking joints K. This not only facilitates the assembling of the range but the particular construction of the joint prevents the waste of heat from the oven in the following manner: Each of the joints is formed with an upper horizontal portion K', a lower horizontal portion K² and a vertical connecting portion K³. In each case the blocks are so arranged that the lower horizontal portion is at the outside of the wall: Therefore in attempting to escape through the joints the heated air will be compelled to pass downward through the vertical portion K³ in order to escape. As the tendency of the heated gas is to rise this particular construction of joint will, to a material extent, prevent the escape of the heated air from the oven. The same stepped joint construction is also employed in the insulator blocks L surrounding the burner section. Another

feature of the oven construction resides in the formation of a supporting pan M which is located above the oven burners N. As shown in Fig. 6 the oven plate M is formed with inverted U-shaped ribs O which are spaced apart and the intermediate portions O' perforated at O².

This construction not only eliminates the danger of burning the article in the oven but also provides greater radiating surface, and the perforations permit of the free circulation of the air. A further feature that increases the efficiency of the range is the enameling of the refractory material of the blocks F, H and H' so as to obtain better deflection of the heat.

While I have shown and described the invention in connection with a construction wherein the openings through the refractory block F are vertically arranged, the invention is not necessarily limited to such a structure, as it would be possible to modify the construction so as to have laterally arranged air passages, and various other changes could be made in the details of construction and arrangements and combinations of parts without departing from the scope of my invention.

What I claim as my invention is:—

1. In a range, the combination with a top plate and an insulator block spaced beneath said plate, formed with a plurality of openings, of burners respectively positioned in said openings and spaced from the walls thereof to form restricted air passages, said burners discharging against said top plate.

2. In a range, the combination with adjacent top plates and an insulator block spaced beneath one of said plates formed with a plurality of openings and with substantially parallel ribs supporting the overlying plate and deflecting products of combustion toward the adjacent top plate and burners respectively positioned in said openings and spaced from the walls thereof to form restricted air passages, said burners discharging against the overlying top plate.

3. In a range, the combination with a top plate, of a refractory block positioned beneath the top plate, a plurality of burners projecting through the refractory block and discharging against the top plate to directly heat the same, the upper surface of said refractory block being enameled to further heat the top plate by reflected radiation.

4. In a range, the combination with a top plate, of a refractory block positioned beneath the top plate, a plurality of burners projecting through the refractory block, the upper surface of said refractory block being enameled to further deflect the heat from said burners toward the top plate, and an oven positioned beneath the rear portion of the top plate and having a top refractory

- wall similarly enameled for deflecting the heat toward the top plate.
5. In a range, the combination with a refractory block, of a plurality of burners arranged to produce heat at the top of the block, an oven having a top wall formed of refractory material, the upper surface of which wall is located above the plane of the top surface of the refractory block, and a substantially horizontal top plate spaced above said burners and oven and forming with the oven a passage for the products of combustion from the burners.
6. In a range, the combination with a refractory block, of a plurality of burners arranged to produce heat at the top of the block, an oven having a top wall formed of refractory material, the upper surface of which wall is located above the plane of the top surface of the refractory block, and a substantially horizontal top plate spaced above the burners and oven, the top wall of the oven being inclined upwardly to gradually reduce the passage through which the hot gases can pass.
7. In a range, the combination with a frame, a top plate carried thereby, burners positioned beneath the top plate, an insulator block also positioned beneath the top
- plate and carried by said frame, said insulator block having projecting ribs forming a support for the top plate.
8. In a range, the combination with a top plate, of a refractory block positioned beneath a portion of the top plate, burners extending through said block, a supply pipe for the burners located beneath the block, said block having a passageway through which air from the portion beneath the block is permitted to pass around the burners and toward the flame end thereof to produce a Bunsen burner effect.
9. In a range, the combination with a top plate, of an oven positioned beneath a portion of said top plate, gas burners positioned beneath a different portion of the top plate, and heat insulating blocks extending around each of the burners and the oven.
10. In a range, the combination with a top plate, of an oven positioned beneath a portion of said plate, gas burners positioned beneath a different portion of the top plate, and heat insulating blocks extending around the oven and partially forming the outside wall of the range.

In testimony whereof I affix my signature.
HENRY D. SCHALL.
